LOAD-DISCHARGING CAR.

Application filed July 10, 1925. Serial No. 42,635.

My invention relates to improvements in load discharging cars and especially of that type adapted to discharge ballast centrally of the rails or to either side thereof or to both sides and center simultaneously.

One object of my invention is to adapt a car of the type indicated so that it will simultaneously place ballast in the center of the track and at the sides thereof in such a manner as to obviate flooding the rails and which will be simple in design.

A second object of the invention is to provide a car having a pair of hoppers, each disposed to one side of the center of the car, which will be adapted to discharge the contents of the two hoppers simultaneously through a central opening in such a manner that the load passing through the openings of the respective hoppers will be deflected centrally of the rails and issue as a unit flow forming a pile of ballast between the rails, so limited in size that the sloping sides thereof will at all times be confined between the rails and below the tops thereof.

A third object of the invention is to so adapt the movable parts of a car of the indicated type that it will be possible to deposit the maximum size heap at the time of minimum door opening and thereafter as the flow of ballast increases to provide for a decrease in the size of the heap.

It is also an object of the invention to deflect the flow of material from two adjacent hoppers through a narrow space disposed centrally of the rails and defined by the free edges of movable doors so that the discharging material from the respective hoppers will commence to flow freely only when the respective doors are in such position that they will positively limit the sloping sides of the pile of material to the extent that the base of the said pile will be confined between rails and below the tops thereof.

Another object of the invention is to provide a simple car of this character which may discharge to both sides of the car and to the center simultaneously, and to so adapt the parts that each of the discharge openings may be operated at the same time but independently of each other and the extent of opening varied in any one without affecting the operation or degree of opening of any of the other discharge openings.

Still another object of the invention is to

provide a car adapted for center and side ballasting wherein the parts are so proportioned and disposed that sections of the flooring of the car will of themselves be sufficient to control the sloping sides of the piles of ballast so as to keep the same free of the rails thereby dispensing with baffle plates, extensions or other accessories on the swinging edges of the door, such as would ordinarily be used for the purpose of deflecting lading beyond a discharge opening.

A more specific object of the invention is to guard against excessive overflow of material at the ends of the doors whereby the ballast left by a discharging moving car embodying my improvements will be of such proportions that the truck parts will be able to move freely over the same.

My invention also resides in certain other features of construction such as will be more fully pointed out hereinafter and claimed.

In said drawing, Figure 1 is a side elevational view of a car having my improvements incorporated therein, the left hand half portion of the car having the outside walls removed for the purpose of better illustrating the interior arrangement of the parts. Figure 2 is a detached plan view on an enlarged scale of one of the inner floor doors. Figure 3 is a plan view of the car having the flooring broken away in the left hand portion of the figure. Figure 4 is a transverse sectional view taken through the lower portion of the car and on a line corresponding substantially to the line 4-4 of Figure 1. Figure 5 is a transverse sectional view taken through the hopper and on a line corresponding substantially to the line 5-5 of Figure 1, the left hand section of the car being taken as facing the end of the hopper and the right-hand portion as facing the center cross-beam. Figure 6 is a transverse sectional view through the hopper similar to Figure 5 except that it shows the doors in a different relation. Figure 7 is a diagrammatic sectional view taken through the car illustrating different ballasting results obtained under various conditions of door openings. Figure 8 is a diagrammatic view illustrating a section of ballasted roadbed and illustrates the position of ballast as deposited by a car embodying my improvements, said ballast being shown in relation to the track and certain of the car parts.

2
And Figure 9 is a section of another car corresponding to my prior Patent 937,416 for comparative purposes.

On said drawings A—A denote broadly the side walls of the car; B—B the fixed end walls of the car; C the longitudinal center sill; D—D transversely extending sloping walls defining the opposite ends of dumping hoppers; E—E convertible floor sections each adapted to form a portion of the level floor of the car in one position, and in another position, a continuation of one of the sloping floor portions D; F—F fixed floor sections each forming, with one 10 of the convertible floors E, a level floor extending from the end of the car to the end of the adjacent hopper section; G longitudinally extending hopper sections extending between the sloping walls D—D, there being 15 two sets of hopper sections per car arranged in pairs on opposite sides of the center sill C, said hopper sections being divided longitudinally of the car by a transversely extending cross-beam H; J—J baffle plates 20 extending transversely of the car adjacent the respective ends of the hopper sections G—G; K—K the rails on which the car is 25 adapted to stand; L one of the axles; M one of the wheels of the car; and N one of the 30 journal boxes for the axles.

Each side wall A of the car includes a side sheet 10, side stakes 11, and upper and lower reinforcing marginal members as indicated at 12 and 13 respectively. The 35 fixed end walls B each includes an end sheet 14 and a reinforcing top marginal member 15; the center sill C includes a ridge shaped hood 16 and two flanged A. R. A. center sill members 17—17 each formed at 40 its lowermost margin with an outwardly projecting flange 18. The transverse walls D includes sloping floor plates 19 each having vertically depending portions 20—20 constituting one of the end walls of the 45 pair of transversely aligned hopper sections G—G, said sloping floor plates being secured to and supported by a transversely extending beam 21. Each convertible floor section E is pivotally mounted on hinge 50 brackets 22 carried by the corresponding beam 21 and is adapted to form, in one position, a continuation of the sloping floor sheet 19 and, in another position, a portion of a level floor substantially in alignment 55 with the top of the center sill hood 16. Each fixed floor section F includes a floor sheet 23 extending transversely across the car.

The transverse cross-beam H includes a channel shaped member 43 extending transversely of the car and disposed with the top thereof substantially on the same level as the end floors F and inclined shedding plates 143 formed with vertically depending wall portions 243 which conform to the shape of 60 the lower V-shaped hopper portion, said

vertical wall portions 143 being spaced apart from each other an appreciable distance and braced by brackets 137 secured to the respective vertical wall portions 143.

Each hopper G includes a lower V-shaped section having inner and outer discharge openings respectively adapted to be closed by inner door 24 and outer door 25. Above said doors each hopper, on the inner side thereof, is defined by the center sill structure and on the outer side by a sloping sheet 26 extending downwardly from its adjacent side wall A at an angle of approximately 40 degrees from the horizontal plane. The lower margin of each of said sheet 26, which terminates somewhat above the level of the lowermost portion of the center sill, is suitably reinforced by an angle member 27. Said inner and outer doors are hinged on a common pivot 28 disposed just below the apex of the V-shaped hopper and which preferably consists of a longitudinally extending shaft member supported in brackets 29, respectively disposed at each end of the hopper and at the central crossbeam H, the doors being 30 suitably cut away as indicated at 30 to clear said brackets. The said doors are hinged- 35 ly mounted on the shaft 28 by means of a butt hinge arrangement formed of a plurality of longitudinally extending plates 31—31^a formed with hinge eyes and secured to each of the doors, the hinge portions 31—31^a on the outer door 25 being alternated with the corresponding hinge portions of the adjacent door 24 thereby providing a continuous sealing hinge joint throughout the 40 length of the hoppers. Each of the doors 24 and 25 is preferably adapted to extend continuously beneath the central cross beam H and for an appreciable distance beyond 45 each vertical end hopper wall 20 at the respective ends of the longitudinal hoppers. The transverse baffle plates J—J are formed to extend from side to side of the car and are disposed adjacent the ends of the respective 50 doors 24 and 25, said baffle plates being preferably formed of two plate sections 32 and 33 overlappingly joined at the center of the car as indicated at 34 and braced to the center sill by a longitudinal brace 35 and 55 to the respective sides of the car by gussets 36—36. Said baffle plates are spaced appreciably from the vertical hopper end walls and maintained in fixed relation thereto by 60 spacing members 137 which are secured to said baffle plates and wall 20. Said baffle plates are flanged at 37 to conform to the 65 sloping floor 19 of the fixed end floor portion D and are extended outwardly beyond the side edges of the respective doors 24 and 25 and downwardly beyond the pivotal centers of the said doors.

A V-shaped arrangement of doors to discharge the entire load to either side of the car or centrally of the rails is, broadly, old 130

- in the art, one such instance being shown in my prior U. S. Patent 937,416, dated Oct. 19, 1909, one of the views of which is herewith reproduced as Figure 9. In the construction disclosed in said prior patent, the hoppers are disposed at such a distance above the rail that the inner doors 100 are intercepted by the lower portion of the center sill 101 and the free edges of said inner doors are so spaced from each other that the material discharging between the free edges of the inner doors will issue in two separate streams throughout the greater part of the movement of the doors and the material does not merge into a unit stream until the doors are nearly fully opened. To more clearly bring out the improvements of the present invention as compared with the prior art and said patent specified with the rails added to show the relation of parts, I have added to Figure 9, to exactly the same scale as the rest of the car shown in my said prior patent, the rails 102 and a pile of lading indicated by conventional dotted lines 103—103, a pile of ballast with the sides thereof sloping on a ratio of $1\frac{1}{2}$ to 1 base to height ratio which is an accepted standard ratio for ballast. It will be noted that the base of said pile is confined between the rails and below the tops thereof. As will be seen by reference to said Fig. 9, the inner doors 100, when opened to form a continuation of the outer doors 104, have their free edges adjacent the sloping sides 103 of the pile as above defined, but in order to derive the best results in ballasting it is desirable that the doors operate to limit the heap of ballast and maintain the same away from the rails during substantially the entire range of movement of the door during which the material flows freely from the car. It is obvious that the pile would have a wider base and its apex higher, if the doors 100 were held in any higher position than that shown and while permitting discharge so that the rails would be flooded.
- In the present invention I overcome the tendency to flood the rails by so proportioning the parts in relation to the rails and so disposing the adjacent hoppers relatively to each other and to the rails that the material from the pair of inner doors 24—24 will only commence to flow freely when the doors are in a position to control the lading and maintain the base of the pile below the tops of the rails throughout the entire range of movement during which free flow of material between the edges of said doors takes place.
- The doors 24 and 25 are rigidified longitudinally by beam members 38 and 39 respectively disposed adjacent the hinge and free edges of the doors and said doors are further braced transversely by a series of braces as indicated at 40 and 41. The mar-
- ginal edge of each inner door is depressed or deflected to present, as at 42, a suitable rigidifying means or flange for the edge of the door, said flange being preferably formed to extend at an appreciable angle to the main plane of the door. Said flange 42, when the door is in closed position, seats beneath the outstanding flange 18 of the adjacent center sill member 17. When the said inner door 24 is in closed position, it extends from the lowermost portion of the center sill at an angle of approximately 40 degrees from the horizontal plane and operates to direct lading to its adjacent discharge openings. Said inner doors 24—24, as they swing downwardly to discharge centrally of the rails, have their free edges approach relatively to each other until such time as the main portions of the doors are in a substantially horizontal position at which time the distance between the free edges of the respective doors, as indicated at "a" in Fig. 7, will be less than the opening between each door and corresponding center sill, as indicated at "b". Therefore, the lading discharging through the two larger openings ⁸⁹ ⁹⁰ ⁹¹ ⁹² ⁹³ ⁹⁴ ⁹⁵ ⁹⁶ ⁹⁷ ⁹⁸ ⁹⁹ ¹⁰⁰ ¹⁰¹ ¹⁰² ¹⁰³ ¹⁰⁴ ¹⁰⁵ ¹⁰⁶ ¹⁰⁷ ¹⁰⁸ ¹⁰⁹ ¹¹⁰ ¹¹¹ ¹¹² ¹¹³ ¹¹⁴ ¹¹⁵ ¹¹⁶ ¹¹⁷ ¹¹⁸ ¹¹⁹ ¹²⁰ ¹²¹ ¹²² ¹²³ ¹²⁴ ¹²⁵ ¹²⁶ ¹²⁷ ¹²⁸ ¹²⁹ ¹³⁰ ¹³¹ ¹³² ¹³³ ¹³⁴ ¹³⁵ ¹³⁶ ¹³⁷ ¹³⁸ ¹³⁹ ¹⁴⁰ ¹⁴¹ ¹⁴² ¹⁴³ ¹⁴⁴ ¹⁴⁵ ¹⁴⁶ ¹⁴⁷ ¹⁴⁸ ¹⁴⁹ ¹⁵⁰ ¹⁵¹ ¹⁵² ¹⁵³ ¹⁵⁴ ¹⁵⁵ ¹⁵⁶ ¹⁵⁷ ¹⁵⁸ ¹⁵⁹ ¹⁶⁰ ¹⁶¹ ¹⁶² ¹⁶³ ¹⁶⁴ ¹⁶⁵ ¹⁶⁶ ¹⁶⁷ ¹⁶⁸ ¹⁶⁹ ¹⁷⁰ ¹⁷¹ ¹⁷² ¹⁷³ ¹⁷⁴ ¹⁷⁵ ¹⁷⁶ ¹⁷⁷ ¹⁷⁸ ¹⁷⁹ ¹⁸⁰ ¹⁸¹ ¹⁸² ¹⁸³ ¹⁸⁴ ¹⁸⁵ ¹⁸⁶ ¹⁸⁷ ¹⁸⁸ ¹⁸⁹ ¹⁹⁰ ¹⁹¹ ¹⁹² ¹⁹³ ¹⁹⁴ ¹⁹⁵ ¹⁹⁶ ¹⁹⁷ ¹⁹⁸ ¹⁹⁹ ²⁰⁰ ²⁰¹ ²⁰² ²⁰³ ²⁰⁴ ²⁰⁵ ²⁰⁶ ²⁰⁷ ²⁰⁸ ²⁰⁹ ²¹⁰ ²¹¹ ²¹² ²¹³ ²¹⁴ ²¹⁵ ²¹⁶ ²¹⁷ ²¹⁸ ²¹⁹ ²²⁰ ²²¹ ²²² ²²³ ²²⁴ ²²⁵ ²²⁶ ²²⁷ ²²⁸ ²²⁹ ²³⁰ ²³¹ ²³² ²³³ ²³⁴ ²³⁵ ²³⁶ ²³⁷ ²³⁸ ²³⁹ ²⁴⁰ ²⁴¹ ²⁴² ²⁴³ ²⁴⁴ ²⁴⁵ ²⁴⁶ ²⁴⁷ ²⁴⁸ ²⁴⁹ ²⁵⁰ ²⁵¹ ²⁵² ²⁵³ ²⁵⁴ ²⁵⁵ ²⁵⁶ ²⁵⁷ ²⁵⁸ ²⁵⁹ ²⁶⁰ ²⁶¹ ²⁶² ²⁶³ ²⁶⁴ ²⁶⁵ ²⁶⁶ ²⁶⁷ ²⁶⁸ ²⁶⁹ ²⁷⁰ ²⁷¹ ²⁷² ²⁷³ ²⁷⁴ ²⁷⁵ ²⁷⁶ ²⁷⁷ ²⁷⁸ ²⁷⁹ ²⁸⁰ ²⁸¹ ²⁸² ²⁸³ ²⁸⁴ ²⁸⁵ ²⁸⁶ ²⁸⁷ ²⁸⁸ ²⁸⁹ ²⁹⁰ ²⁹¹ ²⁹² ²⁹³ ²⁹⁴ ²⁹⁵ ²⁹⁶ ²⁹⁷ ²⁹⁸ ²⁹⁹ ³⁰⁰ ³⁰¹ ³⁰² ³⁰³ ³⁰⁴ ³⁰⁵ ³⁰⁶ ³⁰⁷ ³⁰⁸ ³⁰⁹ ³¹⁰ ³¹¹ ³¹² ³¹³ ³¹⁴ ³¹⁵ ³¹⁶ ³¹⁷ ³¹⁸ ³¹⁹ ³²⁰ ³²¹ ³²² ³²³ ³²⁴ ³²⁵ ³²⁶ ³²⁷ ³²⁸ ³²⁹ ³³⁰ ³³¹ ³³² ³³³ ³³⁴ ³³⁵ ³³⁶ ³³⁷ ³³⁸ ³³⁹ ³⁴⁰ ³⁴¹ ³⁴² ³⁴³ ³⁴⁴ ³⁴⁵ ³⁴⁶ ³⁴⁷ ³⁴⁸ ³⁴⁹ ³⁵⁰ ³⁵¹ ³⁵² ³⁵³ ³⁵⁴ ³⁵⁵ ³⁵⁶ ³⁵⁷ ³⁵⁸ ³⁵⁹ ³⁶⁰ ³⁶¹ ³⁶² ³⁶³ ³⁶⁴ ³⁶⁵ ³⁶⁶ ³⁶⁷ ³⁶⁸ ³⁶⁹ ³⁷⁰ ³⁷¹ ³⁷² ³⁷³ ³⁷⁴ ³⁷⁵ ³⁷⁶ ³⁷⁷ ³⁷⁸ ³⁷⁹ ³⁸⁰ ³⁸¹ ³⁸² ³⁸³ ³⁸⁴ ³⁸⁵ ³⁸⁶ ³⁸⁷ ³⁸⁸ ³⁸⁹ ³⁹⁰ ³⁹¹ ³⁹² ³⁹³ ³⁹⁴ ³⁹⁵ ³⁹⁶ ³⁹⁷ ³⁹⁸ ³⁹⁹ ⁴⁰⁰ ⁴⁰¹ ⁴⁰² ⁴⁰³ ⁴⁰⁴ ⁴⁰⁵ ⁴⁰⁶ ⁴⁰⁷ ⁴⁰⁸ ⁴⁰⁹ ⁴¹⁰ ⁴¹¹ ⁴¹² ⁴¹³ ⁴¹⁴ ⁴¹⁵ ⁴¹⁶ ⁴¹⁷ ⁴¹⁸ ⁴¹⁹ ⁴²⁰ ⁴²¹ ⁴²² ⁴²³ ⁴²⁴ ⁴²⁵ ⁴²⁶ ⁴²⁷ ⁴²⁸ ⁴²⁹ ⁴³⁰ ⁴³¹ ⁴³² ⁴³³ ⁴³⁴ ⁴³⁵ ⁴³⁶ ⁴³⁷ ⁴³⁸ ⁴³⁹ ⁴⁴⁰ ⁴⁴¹ ⁴⁴² ⁴⁴³ ⁴⁴⁴ ⁴⁴⁵ ⁴⁴⁶ ⁴⁴⁷ ⁴⁴⁸ ⁴⁴⁹ ⁴⁵⁰ ⁴⁵¹ ⁴⁵² ⁴⁵³ ⁴⁵⁴ ⁴⁵⁵ ⁴⁵⁶ ⁴⁵⁷ ⁴⁵⁸ ⁴⁵⁹ ⁴⁶⁰ ⁴⁶¹ ⁴⁶² ⁴⁶³ ⁴⁶⁴ ⁴⁶⁵ ⁴⁶⁶ ⁴⁶⁷ ⁴⁶⁸ ⁴⁶⁹ ⁴⁷⁰ ⁴⁷¹ ⁴⁷² ⁴⁷³ ⁴⁷⁴ ⁴⁷⁵ ⁴⁷⁶ ⁴⁷⁷ ⁴⁷⁸ ⁴⁷⁹ ⁴⁸⁰ ⁴⁸¹ ⁴⁸² ⁴⁸³ ⁴⁸⁴ ⁴⁸⁵ ⁴⁸⁶ ⁴⁸⁷ ⁴⁸⁸ ⁴⁸⁹ ⁴⁹⁰ ⁴⁹¹ ⁴⁹² ⁴⁹³ ⁴⁹⁴ ⁴⁹⁵ ⁴⁹⁶ ⁴⁹⁷ ⁴⁹⁸ ⁴⁹⁹ ⁵⁰⁰ ⁵⁰¹ ⁵⁰² ⁵⁰³ ⁵⁰⁴ ⁵⁰⁵ ⁵⁰⁶ ⁵⁰⁷ ⁵⁰⁸ ⁵⁰⁹ ⁵¹⁰ ⁵¹¹ ⁵¹² ⁵¹³ ⁵¹⁴ ⁵¹⁵ ⁵¹⁶ ⁵¹⁷ ⁵¹⁸ ⁵¹⁹ ⁵²⁰ ⁵²¹ ⁵²² ⁵²³ ⁵²⁴ ⁵²⁵ ⁵²⁶ ⁵²⁷ ⁵²⁸ ⁵²⁹ ⁵³⁰ ⁵³¹ ⁵³² ⁵³³ ⁵³⁴ ⁵³⁵ ⁵³⁶ ⁵³⁷ ⁵³⁸ ⁵³⁹ ⁵⁴⁰ ⁵⁴¹ ⁵⁴² ⁵⁴³ ⁵⁴⁴ ⁵⁴⁵ ⁵⁴⁶ ⁵⁴⁷ ⁵⁴⁸ ⁵⁴⁹ ⁵⁵⁰ ⁵⁵¹ ⁵⁵² ⁵⁵³ ⁵⁵⁴ ⁵⁵⁵ ⁵⁵⁶ ⁵⁵⁷ ⁵⁵⁸ ⁵⁵⁹ ⁵⁶⁰ ⁵⁶¹ ⁵⁶² ⁵⁶³ ⁵⁶⁴ ⁵⁶⁵ ⁵⁶⁶ ⁵⁶⁷ ⁵⁶⁸ ⁵⁶⁹ ⁵⁷⁰ ⁵⁷¹ ⁵⁷² ⁵⁷³ ⁵⁷⁴ ⁵⁷⁵ ⁵⁷⁶ ⁵⁷⁷ ⁵⁷⁸ ⁵⁷⁹ ⁵⁸⁰ ⁵⁸¹ ⁵⁸² ⁵⁸³ ⁵⁸⁴ ⁵⁸⁵ ⁵⁸⁶ ⁵⁸⁷ ⁵⁸⁸ ⁵⁸⁹ ⁵⁹⁰ ⁵⁹¹ ⁵⁹² ⁵⁹³ ⁵⁹⁴ ⁵⁹⁵ ⁵⁹⁶ ⁵⁹⁷ ⁵⁹⁸ ⁵⁹⁹ ⁶⁰⁰ ⁶⁰¹ ⁶⁰² ⁶⁰³ ⁶⁰⁴ ⁶⁰⁵ ⁶⁰⁶ ⁶⁰⁷ ⁶⁰⁸ ⁶⁰⁹ ⁶¹⁰ ⁶¹¹ ⁶¹² ⁶¹³ ⁶¹⁴ ⁶¹⁵ ⁶¹⁶ ⁶¹⁷ ⁶¹⁸ ⁶¹⁹ ⁶²⁰ ⁶²¹ ⁶²² ⁶²³ ⁶²⁴ ⁶²⁵ ⁶²⁶ ⁶²⁷ ⁶²⁸ ⁶²⁹ ⁶³⁰ ⁶³¹ ⁶³² ⁶³³ ⁶³⁴ ⁶³⁵ ⁶³⁶ ⁶³⁷ ⁶³⁸ ⁶³⁹ ⁶⁴⁰ ⁶⁴¹ ⁶⁴² ⁶⁴³ ⁶⁴⁴ ⁶⁴⁵ ⁶⁴⁶ ⁶⁴⁷ ⁶⁴⁸ ⁶⁴⁹ ⁶⁵⁰ ⁶⁵¹ ⁶⁵² ⁶⁵³ ⁶⁵⁴ ⁶⁵⁵ ⁶⁵⁶ ⁶⁵⁷ ⁶⁵⁸ ⁶⁵⁹ ⁶⁶⁰ ⁶⁶¹ ⁶⁶² ⁶⁶³ ⁶⁶⁴ ⁶⁶⁵ ⁶⁶⁶ ⁶⁶⁷ ⁶⁶⁸ ⁶⁶⁹ ⁶⁷⁰ ⁶⁷¹ ⁶⁷² ⁶⁷³ ⁶⁷⁴ ⁶⁷⁵ ⁶⁷⁶ ⁶⁷⁷ ⁶⁷⁸ ⁶⁷⁹ ⁶⁸⁰ ⁶⁸¹ ⁶⁸² ⁶⁸³ ⁶⁸⁴ ⁶⁸⁵ ⁶⁸⁶ ⁶⁸⁷ ⁶⁸⁸ ⁶⁸⁹ ⁶⁹⁰ ⁶⁹¹ ⁶⁹² ⁶⁹³ ⁶⁹⁴ ⁶⁹⁵ ⁶⁹⁶ ⁶⁹⁷ ⁶⁹⁸ ⁶⁹⁹ ⁷⁰⁰ ⁷⁰¹ ⁷⁰² ⁷⁰³ ⁷⁰⁴ ⁷⁰⁵ ⁷⁰⁶ ⁷⁰⁷ ⁷⁰⁸ ⁷⁰⁹ ⁷¹⁰ ⁷¹¹ ⁷¹² ⁷¹³ ⁷¹⁴ ⁷¹⁵ ⁷¹⁶ ⁷¹⁷ ⁷¹⁸ ⁷¹⁹ ⁷²⁰ ⁷²¹ ⁷²² ⁷²³ ⁷²⁴ ⁷²⁵ ⁷²⁶ ⁷²⁷ ⁷²⁸ ⁷²⁹ ⁷³⁰ ⁷³¹ ⁷³² ⁷³³ ⁷³⁴ ⁷³⁵ ⁷³⁶ ⁷³⁷ ⁷³⁸ ⁷³⁹ ⁷⁴⁰ ⁷⁴¹ ⁷⁴² ⁷⁴³ ⁷⁴⁴ ⁷⁴⁵ ⁷⁴⁶ ⁷⁴⁷ ⁷⁴⁸ ⁷⁴⁹ ⁷⁵⁰ ⁷⁵¹ ⁷⁵² ⁷⁵³ ⁷⁵⁴ ⁷⁵⁵ ⁷⁵⁶ ⁷⁵⁷ ⁷⁵⁸ ⁷⁵⁹ ⁷⁶⁰ ⁷⁶¹ ⁷⁶² ⁷⁶³ ⁷⁶⁴ ⁷⁶⁵ ⁷⁶⁶ ⁷⁶⁷ ⁷⁶⁸ ⁷⁶⁹ ⁷⁷⁰ ⁷⁷¹ ⁷⁷² ⁷⁷³ ⁷⁷⁴ ⁷⁷⁵ ⁷⁷⁶ ⁷⁷⁷ ⁷⁷⁸ ⁷⁷⁹ ⁷⁸⁰ ⁷⁸¹ ⁷⁸² ⁷⁸³ ⁷⁸⁴ ⁷⁸⁵ ⁷⁸⁶ ⁷⁸⁷ ⁷⁸⁸ ⁷⁸⁹ ⁷⁹⁰ ⁷⁹¹ ⁷⁹² ⁷⁹³ ⁷⁹⁴ ⁷⁹⁵ ⁷⁹⁶ ⁷⁹⁷ ⁷⁹⁸ ⁷⁹⁹ ⁸⁰⁰ ⁸⁰¹ ⁸⁰² ⁸⁰³ ⁸⁰⁴ ⁸⁰⁵ ⁸⁰⁶ ⁸⁰⁷ ⁸⁰⁸ ⁸⁰⁹ ⁸¹⁰ ⁸¹¹ ⁸¹² ⁸¹³ ⁸¹⁴ ⁸¹⁵ ⁸¹⁶ ⁸¹⁷ ⁸¹⁸ ⁸¹⁹ ⁸²⁰ ⁸²¹ ⁸²² ⁸²³ ⁸²⁴ ⁸²⁵ ⁸²⁶ ⁸²⁷ ⁸²⁸ ⁸²⁹ ⁸³⁰ ⁸³¹ ⁸³² ⁸³³ ⁸³⁴ ⁸³⁵ ⁸³⁶ ⁸³⁷ ⁸³⁸ ⁸³⁹ ⁸⁴⁰ ⁸⁴¹ ⁸⁴² ⁸⁴³ ⁸⁴⁴ ⁸⁴⁵ ⁸⁴⁶ ⁸⁴⁷ ⁸⁴⁸ ⁸⁴⁹ ⁸⁵⁰ ⁸⁵¹ ⁸⁵² ⁸⁵³ ⁸⁵⁴ ⁸⁵⁵ ⁸⁵⁶ ⁸⁵⁷ ⁸⁵⁸ ⁸⁵⁹ ⁸⁶⁰ ⁸⁶¹ ⁸⁶² ⁸⁶³ ⁸⁶⁴ ⁸⁶⁵ ⁸⁶⁶ ⁸⁶⁷ ⁸⁶⁸ ⁸⁶⁹ ⁸⁷⁰ ⁸⁷¹ ⁸⁷² ⁸⁷³ ⁸⁷⁴ ⁸⁷⁵ ⁸⁷⁶ ⁸⁷⁷ ⁸⁷⁸ ⁸⁷⁹ ⁸⁸⁰ ⁸⁸¹ ⁸⁸² ⁸⁸³ ⁸⁸⁴ ⁸⁸⁵ ⁸⁸⁶ ⁸⁸⁷ ⁸⁸⁸ ⁸⁸⁹ ⁸⁹⁰ ⁸⁹¹ ⁸⁹² ⁸⁹³ ⁸⁹⁴ ⁸⁹⁵ ⁸⁹⁶ ⁸⁹⁷ ⁸⁹⁸ ⁸⁹⁹ ⁹⁰⁰ ⁹⁰¹ ⁹⁰² ⁹⁰³ ⁹⁰⁴ ⁹⁰⁵ ⁹⁰⁶ ⁹⁰⁷ ⁹⁰⁸ ⁹⁰⁹ ⁹¹⁰ ⁹¹¹ ⁹¹² ⁹¹³ ⁹¹⁴ ⁹¹⁵ ⁹¹⁶ ⁹¹⁷ ⁹¹⁸ ⁹¹⁹ ⁹²⁰ ⁹²¹ ⁹²² ⁹²³ ⁹²⁴ ⁹²⁵ ⁹²⁶ ⁹²⁷ ⁹²⁸ ⁹²⁹ ⁹³⁰ ⁹³¹ ⁹³² ⁹³³ ⁹³⁴ ⁹³⁵ ⁹³⁶ ⁹³⁷ ⁹³⁸ ⁹³⁹ ⁹⁴⁰ ⁹⁴¹ ⁹⁴² ⁹⁴³ ⁹⁴⁴ ⁹⁴⁵ ⁹⁴⁶ ⁹⁴⁷ ⁹⁴⁸ ⁹⁴⁹ ⁹⁵⁰ ⁹⁵¹ ⁹⁵² ⁹⁵³ ⁹⁵⁴ ⁹⁵⁵ ⁹⁵⁶ ⁹⁵⁷ ⁹⁵⁸ ⁹⁵⁹ ⁹⁶⁰ ⁹⁶¹ ⁹⁶² ⁹⁶³ ⁹⁶⁴ ⁹⁶⁵ ⁹⁶⁶ ⁹⁶⁷ ⁹⁶⁸ ⁹⁶⁹ ⁹⁷⁰ ⁹⁷¹ ⁹⁷² ⁹⁷³ ⁹⁷⁴ ⁹⁷⁵ ⁹⁷⁶ ⁹⁷⁷ ⁹⁷⁸ ⁹⁷⁹ ⁹⁸⁰ ⁹⁸¹ ⁹⁸² ⁹⁸³ ⁹⁸⁴ ⁹⁸⁵ ⁹⁸⁶ ⁹⁸⁷ ⁹⁸⁸ ⁹⁸⁹ ⁹⁹⁰ ⁹⁹¹ ⁹⁹² ⁹⁹³ ⁹⁹⁴ ⁹⁹⁵ ⁹⁹⁶ ⁹⁹⁷ ⁹⁹⁸ ⁹⁹⁹ ¹⁰⁰⁰ ¹⁰⁰¹ ¹⁰⁰² ¹⁰⁰³ ¹⁰⁰⁴ ¹⁰⁰⁵ ¹⁰⁰⁶ ¹⁰⁰⁷ ¹⁰⁰⁸ ¹⁰⁰⁹ ¹⁰¹⁰ ¹⁰¹¹ ¹⁰¹² ¹⁰¹³ ¹⁰¹⁴ ¹⁰¹⁵ ¹⁰¹⁶ ¹⁰¹⁷ ¹⁰¹⁸ ¹⁰¹⁹ ¹⁰²⁰ ¹⁰²¹ ¹⁰²² ¹⁰²³ ¹⁰²⁴ ¹⁰²⁵ ¹⁰²⁶ ¹⁰²⁷ ¹⁰²⁸ ¹⁰²⁹ ¹⁰³⁰ ¹⁰³¹ ¹⁰³² ¹⁰³³ ¹⁰³⁴ ¹⁰³⁵ ¹⁰³⁶ ¹⁰³⁷ ¹⁰³⁸ ¹⁰³⁹ ¹⁰⁴⁰ ¹⁰⁴¹ ¹⁰⁴² ¹⁰⁴³ ¹⁰⁴⁴ ¹⁰⁴⁵ ¹⁰⁴⁶ ¹⁰⁴⁷ ¹⁰⁴⁸ ¹⁰⁴⁹ ¹⁰⁵⁰ ¹⁰⁵¹ ¹⁰⁵² ¹⁰⁵³ ¹⁰⁵⁴ ¹⁰⁵⁵ ¹⁰⁵⁶ ¹⁰⁵⁷ ¹⁰⁵⁸ ¹⁰⁵⁹ ¹⁰⁶⁰ ¹⁰⁶¹ ¹⁰⁶² ¹⁰⁶³ ¹⁰⁶⁴ ¹⁰⁶⁵ ¹⁰⁶⁶ ¹⁰⁶⁷ ¹⁰⁶⁸ ¹⁰⁶⁹ ¹⁰⁷⁰ ¹⁰⁷¹ ¹⁰⁷² ¹⁰⁷³ ¹⁰⁷⁴ ¹⁰⁷⁵ ¹⁰⁷⁶ ¹⁰⁷⁷ ¹⁰⁷⁸ ¹⁰⁷⁹ ¹⁰⁸⁰ ¹⁰⁸¹ ¹⁰⁸² ¹⁰⁸³ ¹⁰⁸⁴ ¹⁰⁸⁵ ¹⁰⁸⁶ ¹⁰⁸⁷ ¹⁰⁸⁸ ¹⁰⁸⁹ ¹⁰⁹⁰ ¹⁰⁹¹ ¹⁰⁹² ¹⁰⁹³ ¹⁰⁹⁴ ¹⁰⁹⁵ ¹⁰⁹⁶ ¹⁰⁹⁷ ¹⁰⁹⁸ ¹⁰⁹⁹ ¹¹⁰⁰ ¹¹⁰¹ ¹¹⁰² ¹¹⁰³ ¹¹⁰⁴ ¹¹⁰⁵ ¹¹⁰⁶ ¹¹⁰⁷ ¹¹⁰⁸ ¹¹⁰⁹ ¹¹¹⁰ ¹¹¹¹ ¹¹¹² ¹¹¹³ ¹¹¹⁴ ¹¹¹⁵ ¹¹¹⁶ ¹¹¹⁷ ¹¹¹⁸ ¹¹¹⁹ ¹¹²⁰ ¹¹²¹ ¹¹²² ¹¹²³ ¹¹²⁴ ¹¹²⁵ ¹¹²⁶ ¹¹²⁷ ¹¹²⁸ ¹¹²⁹ ¹¹³⁰ ¹¹³¹ ¹¹³² ¹¹³³ ¹¹³⁴ ¹¹³⁵ ¹¹³⁶ ¹¹³⁷ ¹¹³⁸ ¹¹³⁹ ¹¹⁴⁰ ¹¹⁴¹ ¹¹⁴² ¹¹⁴³ ¹¹⁴⁴ ¹¹⁴⁵ ¹¹⁴⁶ ¹¹⁴⁷ ¹¹⁴⁸ ¹¹⁴⁹ ¹¹⁵⁰ ¹¹⁵¹ ¹¹⁵² ¹¹⁵³ ¹¹⁵⁴ ¹¹⁵⁵ ¹¹⁵⁶ ¹¹⁵⁷ ¹¹⁵⁸ ¹¹⁵⁹ ¹¹⁶⁰ ¹¹⁶¹ ¹¹⁶² ¹¹⁶³ ¹¹⁶⁴ ¹¹⁶⁵ ¹¹⁶⁶ ¹¹⁶⁷ ¹¹⁶⁸ ¹¹⁶⁹ ¹¹⁷⁰ ¹¹⁷¹ ¹¹⁷² ¹¹⁷³ ¹¹⁷⁴ ¹¹⁷⁵ ¹¹⁷⁶ ¹¹⁷⁷ ¹¹⁷⁸ ¹¹⁷⁹ ¹¹⁸⁰ ¹¹⁸¹ ¹¹⁸² ¹¹⁸³ ¹¹⁸⁴ ¹¹⁸⁵ ¹¹⁸⁶ ¹¹⁸⁷ ¹¹⁸⁸ ¹¹⁸⁹ ¹¹⁹⁰ ¹¹⁹¹ ¹¹⁹² ¹¹⁹³ ¹¹⁹⁴ ¹¹⁹⁵ ¹¹⁹⁶ ¹¹⁹⁷ ¹¹⁹⁸ ¹¹⁹⁹ ¹²⁰⁰ ¹²⁰¹ ¹²⁰² ¹²⁰³ ¹²⁰⁴ ¹²⁰⁵ ¹²⁰⁶ ¹²⁰⁷ ¹²⁰⁸ ¹²⁰⁹ ¹²¹⁰ ¹²¹¹ ¹²¹² ¹²¹³ ¹²¹⁴ ¹²¹⁵ ¹²¹⁶ ¹²¹⁷ ¹²¹⁸ ¹²¹⁹ ¹²²⁰ ¹²²¹

1
baffle plate is extended downwardly a sufficient distance below the axle to limit the heap of ballast so that the axle L will readily pass over the same. Similarly the 5 heap of ballast at the side of the car may be limited as indicated at 47 to permit the journal box N to pass over the same by positioning the side doors as indicated in Figure 7. Reference to Fig. 8 indicates the 10 outline of the ballast deposited between the rails when the free edges of the respective inner doors are positioned so that the said free edges coincides substantially with the lower margin of the baffle plates J. A slope 15 for the doors of 40 degrees from the horizontal plane is particularly efficient inasmuch as it provides a plane on which lading of average density will readily flow and also provides an opening, when the door 20 is opened, which will prevent arching of the lading above the door inasmuch as the horizontal distance "d" is slightly greater than the vertical distance "e" as will be seen by reference to Fig. 7. It will be noted 25 that the hinge point 28 of the inner doors is substantially on a level with the top of the ballast heap and as said inner doors swing downwardly from their inclined position as a portion of the car floor to the 30 substantially horizontal position and thereafter to an inclined position in continuation of the plane of the outer doors, I am enabled to control the flow of ballast in any 35 position with only so much of door as is actually necessary to bridge the space intermediate the lowermost part of the center sill and the hinge of the door and in this manner avoid the use of cumbersome and heavy extensions or baffles on the doors to 40 deflect the material centrally of the rails and away from the hopper openings.

The inner doors 24 are raised and lowered in unison by means of flexible connections 45 winding on an operating shaft 49 disposed between the center sills, said shaft 49 being rotated by means of a cross shaft 50, said shafts 49 and 50 being operatively connected by worm and gearing 51 preferably disposed in a housing 52. Said cross 55 shaft 50 is disposed rearwardly of the baffle plates J and operated from either end thereof by means of shaft rotating means shown conventionally at 53, the shaft 50 being supported at its outer ends by the gusset plates 36.

Each outer door 25 is adapted to be operated independently of the other outer door or of the inner doors 24. The operation of each of said doors is through the 60 medium of flexible connections 54 winding on a longitudinal shaft 55, each shaft being mounted adjacent the free edge of the door and supported from the center crossbeam by means of a bracket 56 and at the ends 65 of the doors by a bracket 57 and worm gear

housing 58 respectively carried by baffle plates J at the ends of said door. The operation of each longitudinal shaft 55 is effected by a short transverse shaft 59, said shafts being operatively connected by means of worm and gearing shown conventionally at 60 mounted in said housing 58. Each shaft 59 extends through the corresponding gusset plate 36 and rotating and locking means indicated conventionally at 61 are 75 mounted outwardly of said plate.

The flexible connections 48 and 54 for the respective doors 24 and 25 are disposed in the plane of said doors passing through perforations 62 formed therein and the direction of pull on the said flexible connections is reversed by means of sheaves 63 over which the said connections pass. Three flexible connections per door are preferably used, there being one extending through the center crossbeam H and at each end of the door, the latter extending between the baffle plates J and the adjacent, vertically depending hopper wall portion 20.

The arrangement of door operating 90 mechanisms thus permits the operation of the center and both side doors simultaneously and as any one of said set of doors may be operated without affecting the extent of opening or degree of angularity of 95 any of the other sets of doors three operators may ballast from one car without either affecting the work of the others.

It will thus be noted that the disposition 100 of operating shafts and operating mechanisms rearwardly of the baffle plates protects the same from damage as well as insures the safety of the operator against falling boulders which would normally flow over the edges of the door. Furthermore, 105 the disposition of the parts which provide perfect control over the discharging lading and automatically limit the flow of the discharging ballast flowing through the center doors render the operation of a car having 110 my improvements therein a very simple matter, as even if the operator should open the doors to the full extent, the rails will not be flooded.

I have herein shown and described what 115 I now consider the preferred manner of carrying out my invention, but the same is merely illustrative, and I contemplate all changes and modifications that come within the scope of the claims appended hereto. 120

What I claim is:

1. In a dump car, the combination with the center sill thereof; of longitudinally extending hoppers disposed on the opposite sides thereof, each said hopper having a 125 movable sloping side hinged adjacent its lower margin and adapted to abut the center sill when in closed position, said sides being adapted to move in unison to a substantially horizontal position and so formed 130

and proportioned that when in such position the distance between the free edges of the respective sides will be less than the width of the openings between said center sill and 5 movable sides.

2. In a dump car, the combination with a center sill structure; of a dumping hopper at each side of said center sill structure; a door for each of said hoppers, each said door 10 being pivotally mounted adjacent its lower margin and, when in closed position, inclined upwardly therefrom and having the free edge thereof abutting the lowermost portion of the center sill structure, said 15 doors of the respective hoppers being movable in unison and being adapted, as they move downwardly towards each other, to provide an opening between the free edges of the respective doors of gradually decreasing 20 width until such time as the said doors are in a substantially horizontal position, said opening when the doors are in substantially horizontal position being of lesser width than the distance between the center 25 sill structure and said doors.

3. In a car of the character described, the combination with a center sill structure and the sides of the car; of a longitudinal hopper section on each side of the center sill, each 30 said hopper section being defined by end walls and fixed longitudinal portions, said fixed longitudinal portions including the center sill structure on the inner side of the hopper and a downwardly sloping fixed floor 35 for the outer side of the hopper, said last named side terminating somewhat above the lowermost portion of the center sill and spaced away therefrom; doors pivotally mounted centrally of said hopper opening, 40 one of said doors forming a continuation of the outer sloping floor and the other of said doors forming a sloping floor extending between the lower margin of the center sill and the apex of the V-shaped hopper.

4. In a dump car of the character described, the combination with a central, longitudinally extending fixed structure; of a V-shaped hopper disposed on each side of 50 said central structure, one side of each said hopper constituting a shedding plane adapted to extend from the lowermost point of the fixed structure to the apex of the hopper, each said side of the respective hoppers being hingedly mounted adjacent the apex of 55 the hopper and both said sides being movable in unison towards each other to direct lading centrally of the rails.

5. In a dump car of the character described, the combination with the longitudinal center sill of the car; of a V-shaped hopper disposed on either side thereof, each 60 said hopper having outer movable sides and inner movable sides respectively adapted to discharge the entire lading in the car either to the sides of the car or between the rails.

each said hopper having the inner side thereof hinged adjacent the apex of the hopper and having the free edge thereof beneath the center sill thereby constituting an inclined shedding member extending from the lowermost point of the center sill to the apex of the hopper and adapted, when in such position, to direct lading to the outer door, said inner doors of the pair of hoppers being movable in unison and so disposed that, when said doors are in a substantially horizontal position, the space between the free edges thereof represents substantially the minimum door opening through which the material in the respective hoppers may discharge as a unit flow.

6. In a car of the character described, the combination with a longitudinal center sill; of a V-shaped hopper disposed on either side of the center sill, the inner side of each said V-shaped hopper being hinged adjacent the apex of the hopper and, when in closed position, inclined upwardly with its free edge abutting the lowermost point of the center sill, said inner doors of the pair of hoppers, 85 when in closed position, having their free edges spaced from each other and being adapted to move downwardly in unison to discharge lading centrally of the rails, the distance between the free edges of the doors diminishing during the movement of the door from an inclined position to a substantially horizontal position at which time the load being discharged from the car body will form a pile of ballast between the rails 90 having its base confined within the rails on which the car stands and below the tops of said rails assuming the slope of the heap to be based on a slope of $1\frac{1}{2}$ to 1 base to height ratio.

7. In a car of the character described, the combination with a longitudinal center sill; of a V-shaped hopper disposed on either side of the center sill, the inner side of each said V-shaped hopper being hinged adjacent the apex of the hopper and, when in closed position, inclined upwardly with its free edge abutting the lowermost side of the center sill, said inner doors of a pair of hoppers being adapted to move downwardly in unison to discharge lading centrally of the rails, the distance between the free edges of the doors diminishing during the movement of the doors from an inclined to a substantially horizontal position at which time the opening between said doors will be smaller 115 than the distance between the doors and the center sill of the car.

8. In a car of the character described adapted to deposit ballast centrally between the rails, the combination with a longitudinal center sill; of a V-shaped hopper disposed in either side thereof, each said hopper having the inner wall thereof pivoted adjacent the apex of the hopper and, when 125

130 to the sides of the car or between the rails.

- 6 in closed position, inclined upwardly and inwardly towards the center sill of the car with the free edge abutting the lowermost point of the center sill of the car, said inner walls, during the initial opening of the doors of a pair of hoppers, being so disposed as to cause relative approach of the free edges of the pair of doors until such time as the doors are substantially in a horizontal plane 5 when the free edges of the respective doors will be substantially adjacent a line representing the slope of a pile of ballast entirely between the rails with the base of the pile below the top of the rails and the slope of ballast on a ratio of base to height of substantially 1½ to 1. 10 15 20 25 30 35 40 45 50 55 60 65 70 75 80 85 90 95 100 105 110 115 120 125 130
9. In a car of the character described, the combination with a longitudinal center sill; of longitudinal hoppers disposed on either side thereof, each said hopper having incorporated therein a lower V-shaped section formed with an inner and an outer door adapted to discharge the lading either centrally of the rails or to the outer sides thereof, said lower V-shaped section being disposed below the level of the center sills whereby the inner doors will operate either as inclined shedding members to bridge the distance at an angle of substantially 40 degrees from the horizontal plane intermediate the lowermost point of the center sill and the hinge of said door or said doors may open inwardly to discharge the contents of both hoppers simultaneously between the rails. 10 15 20 25 30 35 40 45 50 55 60 65 70 75 80 85 90 95 100 105 110 115 120 125 130
10. In a car of the character described adapted to deposit ballast between the rails on which the car is mounted, the combination with a plurality of V-shaped hoppers spaced from each other, each said hopper having inner sloping walls hinged adjacent the apex of the hopper for the purpose of discharging lading centrally of the rails, said inner walls, when swinging from a normally closed position to a substantially horizontal position, being adapted to provide for a gradually diminishing opening between the free edges of the doors of the respective hoppers until such time as the doors reach a substantially horizontal plane, said doors having each a depressed portion at its outer edge in order that the free edge thereof, when the main body of the door is substantially in a horizontal plane, will lie adjacent a line representing the slope of a pile of ballast with the base of said pile confined between the rails and below the top thereof and assuming the slope of ballast to be on a base to height ratio of substantially 1½ to 1. 10 15 20 25 30 35 40 45 50 55 60 65 70 75 80 85 90 95 100 105 110 115 120 125 130
11. In a car of the character described, the combination with the side walls thereof; of a longitudinal center sill structure disposed centrally of said side walls, said center sill structure including two structural flanged members each having the upper flange there- of inwardly directed and a sloping hood over said structural members; a V-shaped hopper section disposed below level of the center sill, said V-shaped hopper section having sloping sides extending at an angle of approximately 40 degrees from the horizontal plane, said sides of the V-shaped hopper section being hinged adjacent the apex of the hopper and respectively movable to discharge the lading either centrally of the rails or outwardly thereof. 10 15 20 25 30 35 40 45 50 55 60 65 70 75 80 85 90 95 100 105 110 115 120 125 130
12. In a car of the character described adapted to deposit ballast between the rails on which the car is mounted, the combination with a plurality of V-shaped hoppers spaced from each other, each said hopper having the inner wall thereof pivoted adjacent the apex of the hopper and, when in closed position, inclined inwardly and upwardly towards the center of the car, the free edges of said inner doors relatively approaching each other during opening movement from the closed position until such time as the doors occupy a substantially horizontal position, said doors, when near the horizontal plane, being adapted to have the free edges thereof lying adjacent a line representing the slope of a pile of ballast having the base of said pile confined between the rails and below the tops thereof and assuming the slope of the ballast to be on a base to height ratio of substantially 1½ to 1. 10 15 20 25 30 35 40 45 50 55 60 65 70 75 80 85 90 95 100 105 110 115 120 125 130
13. In a car of the character described adapted to deposit ballast between the rails on which the car is mounted, the combination with a plurality of V-shaped hoppers spaced from each other, each said hopper having its inner wall thereof pivoted adjacent the apex of the hopper and, when in closed position, inclined inwardly and upwardly towards the center of the car, the free edges of said inner doors of the pair of hoppers being adapted to swing towards each other during the initial opening movement of the doors to thereby provide for a gradually diminishing opening between the free edges thereof until such time as the free edges of the doors are substantially adjacent a line representing the slope of a pile of ballast having the base of the said pile confined between the rails and below the tops thereof and assuming the slope of the ballast to be on a base to height ratio of substantially 1½ to 1. 10 15 20 25 30 35 40 45 50 55 60 65 70 75 80 85 90 95 100 105 110 115 120 125 130
14. In a dump car adapted to discharge lading to both the center and respective sides of the car simultaneously, the combination with the longitudinal center sill of the car; of a hopper disposed on each side of the center sill, each said hopper having a lower V-shaped portion; a hopper opening in each side of each V-shaped hopper, one of said hopper openings being adapted to discharge outwardly of the rail and the other opening being adapted to discharge 10 15 20 25 30 35 40 45 50 55 60 65 70 75 80 85 90 95 100 105 110 115 120 125 130

- inwardly of the said rail; and outer and inner doors for each said hopper, each said door being hinged adjacent the apex of the hopper and adapted to form, in one position, a sloping floor for the V-shaped hopper section and movable downwardly to form a shedding member to deflect the lading flowing through the discharge opening which it is normally adapted to close, the inner doors of the respective hoppers being so formed and disposed that the lading flowing through the discharge openings which said inner doors are adapted to normally close will issue as a unit flow from a central opening defined by the free edges of the said respective inner doors and deposit a ridge of lading between the rails, said parts being so arranged that the lading will flow freely through said central opening only when the said inner doors are substantially in such position as to so limit the slope of the ridge that the same will be confined between the rails and below the tops thereof, assuming the slopes of the ridge to be based on a $1\frac{1}{2}$ to 1 base to height ratio.
15. In a railway car adapted to simultaneously discharge lading to the center and sides of the car, the combination with two transversely aligned longitudinal hoppers, each said hopper having two adjacent transversely aligned discharge openings respectively adapted for center and side discharge; of a pivotally mounted door member associated with each discharge opening, a pair of such door members extending inwardly from their pivotal centers towards the center of the car to discharge centrally of the rails, each said door member being adapted to form, in one position, the sloping floor of a hopper adapted to direct lading to its adjacent discharge opening and movable from such position to form a shedding member adapted to direct lading away from the discharge opening which it is normally adapted to close, said pair of centrally discharging door members being disposed in such a manner that the discharging material flowing from the two discharge openings which they are adapted to normally close will issue as a unit flow from a central opening extending between the free edges of the said pair of door members and form a central pile between the rails, said discharging material being adapted to flow freely from such central opening only when the respective door members are substantially in a position to limit the sloping sides of a pile of ballast so that the said pile will be confined between the rails, and below the top thereof assuming the slopes of the pile to be based on a $1\frac{1}{2}$ to 1 base to height ratio, the said central doors being adapted to vary the size of the central pile of ballast by variations in the sloping angle of the said doors without affecting the position or flow of the side discharging doors.
16. In a car of the character described, the combination with the side walls thereof; of a longitudinal center sill structure including a plurality of members having webs of extended depth and a surmounting ridge member secured to the webs adjacent the top thereof; a hopper section on each side of said center sill, each said hopper section being defined by one side of the center sill structure, an inner sloping floor section extending outwardly and downwardly from the lower margin of the center sill and an outer sloping floor extending downwardly from the side wall of the car and meeting the inner sloping floor in the form of a V; the lower section of each said V-shaped hopper having the respective sides hinged adjacent the apex of the hopper whereby the entire load in each hopper may be discharged to either side of the rail.
17. In a car of the character described, the combination with a longitudinal hopper including an outwardly swinging door; of transverse baffle plates adjacent the ends of the door; end walls at each end of the hopper, each said end wall including a downwardly sloping portion extending over the baffle plate and having a vertical depending portion spaced inwardly away from said baffle plate; spacing means extending between said vertical depending end wall portion and the transverse baffle plate; and flexible door operating means extending between said vertical hopper end wall and baffle plate.
18. In a car of the character described having a hopper defined by end walls and longitudinally extending sloping walls meeting in the form of a V; the combination with a door formed in one of the sides of said hopper, said door being movable to a downwardly sloping position to form with the adjacent side of the hopper a continuous sloping floor; of a transverse vertical baffle plate at the end of the door, said baffle plate being spaced away from the corresponding hopper end walls; a sheave disposed between said hopper end wall and baffle plate; a shaft disposed adjacent the free edge of the door; and a connection extending between the shaft and the door, said connection being adapted to extend over the sheave.
19. In a car of the character described, the combination with a longitudinal hopper including two movable sides hinged on a common pivotal center, one of said sides being adapted to swing towards the center of the car to discharge the lading between the rails and the other of said sides being adapted to discharge the lading to the outer side of the rail; an operating shaft disposed above each sloping movable side when

in closed position, said shafts being also located beyond the respective free edges of said sides; flexible connections extending between each of said shafts and its corresponding movable side; means for deflecting each flexible connection from a straight line path, said flexible connection being disposed in the plane of the door; and a transversely extending sloping floor extending over each of said flexible connections.

20. In a car of the character described, the combination with a longitudinal hopper having a vertical end wall, said hopper being of substantially V-shape and having one of its sides outwardly and downwardly movable whereby discharge of the load outwardly of the rail may be effected, said side being adapted to extend longitudinally of the car for an appreciable distance beyond the vertical end hopper wall; a transverse baffle plate disposed in the plane of the movable side at each end thereof, said baffle plate being extended outwardly beyond the free edge of the door when the latter is in closed position; a shaft journaled in said baffle plate; and connections extending between the shaft and the door, said connections being disposed between the hopper end wall and the transverse baffle plate.

21. In a dump car, the combination with a longitudinal hopper having an outwardly and downwardly opening door; a transverse baffle plate disposed adjacent the end edge of the door, said baffle plate having a portion thereof extending outwardly beyond the free edge of the door; a longitudinally extending door operating shaft journaled in said transverse baffle plate; a connection from the shaft and the door disposed on one side of the baffle plate; and rotating means for actuating the longitudinal shaft disposed on the opposite side of the baffle plate, said rotating means including: a gear wheel united with the shaft, a worm wheel operatively engaging said gear wheel a housing carried by the baffle plate, said housing enclosing the worm and gear wheels.

22. In a dump car, the combination with

a side wall of the car; of a longitudinal hopper spaced inwardly of said side wall; a dumping door for the hopper; a baffle plate disposed adjacent the end edge of the door, said baffle plate having a portion thereof extending outwardly beyond the free edge of the door; door raising means including: a longitudinally extending operating shaft journaled in said transverse baffle plate and a flexible element connected to the shaft and door, respectively; a gusset plate extending at an angle to said baffle plate and connected thereto and to the side wall of the car; means for rotating the longitudinal shaft including a transversely extending shaft and worm and gearing operatively connecting said shafts, said transverse shaft being carried at the side of the car by the gusset connecting the baffle plate with the side wall of the car; and shaft rotating means for said transverse shaft disposed outwardly of said gusset plate.

23. In a dumping car of the ballast type, longitudinally extending, V-shaped hoppers on opposite sides of the center sill, each of said hoppers including a center dumping door hinged upon a longitudinally extending axis located in a horizontal plane intermediate the planes of the tops of the rails and the bottom of the center sill; and operating mechanism for said center dumping doors and arranged to control their discharging positions; said hinge axes being so located with respect to the rails, and the width of said doors from hinged to free edges being so proportioned that, in any load-discharging position of said doors, the discharged pile will have the sloping sides thereof restricted to passing inwardly of and below the tops of the rails, assuming the character of discharged load as characterized by substantially a $1\frac{1}{2}$ to 1 ratio base to height normal slope.

In witness that I claim the foregoing I have hereunto subscribed my name this 29th day of June, 1925.

ARGYLE CAMPBELL.
